VANCOUVER ISLAND, BRITISH COLUMBIA, CANADA.

ROAD-OIL-SPREADING NOZZLE.

1,243,417.

Specification of Letters Patent. Patented Oct. 16, 1917.

Application filed September 25, 1916. Serial No. 122,075.

To all whom it may concern:

Be it known that we, DAVID W. JOHNSTON, GEORGE G. GIRLING, and SIDNEY S. GIRLING, citizens of the Dominion of Canada, residing at Saanich, Vancouver Island, in the Province of British Columbia, Canada, have invented certain new and useful Improvements in Road-Oil-Spreading Nozzles, of which the following is a specification.

10 This invention relates to an improved means for forcibly delivering a spray of heavy road oil or heat liquefied asphaltum over a road surface.

The material with which traffic roads now 15 require to be dressed, whether road oil or asphaltum, should not only be evenly spread over the surface but be forcibly delivered thereto, as it is thereby enabled to further penetrate the interstices of the road metal, 20 and if the material is to be applied hot, as is necessary with asphaltum and may be desirable with other dressings, the delivery should be as direct as possible that it may not lose its heat before it reaches the road 25 surface.

Road dressing material being of a strongly viscous character is not suitable for expression through small apertures or slits, as such apertures are liable to obstruction and the 30 power necessary to force a viscous material through a small aperture absorbs a considerable amount of power and the apertures or slits are liable to obstruction.

Attempts have been made to use a reasonably 35 large aperture and effect the fine division and dispersion of the spray by imparting a whirling movement to the issuing jet, but in such case the power applied to the material is largely absorbed in imparting 40 the whirling movement, and the finely divided particles are not forcibly delivered to the road surface but practically fall by gravity. Further not being directly delivered to the road surface, if the material is to 45 be used hot, the heat is lost before it reaches the road.

If steam is used to effect the expression and dispersion of the road dressing material the presence of the water of condensation 50 prevents proper adherence of the applied dressing to the material of the road, and if compressed air is delivered with the jet to induce its flow and effect its dispersion the sudden expansion of that air at the nozzle 55 cools the issuing spray.

The invention, which is the subject of this application, has been designed to forcibly deliver the road dressing material in an intact flattened film, direct to the road surface, with substantially the full energy of the 60 power applied to enforce its flow, whereby the material may be delivered hot onto the surface of the road and with force sufficient to insure its penetration.

The invention is particularly described in 65 the following specification, reference being made to the drawings by which it is accompanied, in which:

Figure 1 is a vertical cross section through the opposed delivery nozzles through which 70 the road dressing material is delivered.

Fig. 2 is a longitudinal section of the same.

Fig. 3 is an elevation showing the arrangement of the nozzles across the road width to be treated, and

Fig. 4, a plan of the same.

In these drawings 2 represents the pipe, transverse of the road, to which the road dressing material is delivered under pressure from a reservoir or supply tank which 80 is mounted preferably on a self-propelled vehicle. This tank may have means for maintaining the road dressing material at the required heat to insure sufficient fluidity and adherence to the road metal and its delivery under pressure may be accomplished in any convenient manner, such as by a small rotary pump in the delivery pipe. At intervals in this cross pipe 2 ducts 3 deliver to converging opposed nozzles 4, the axes of 90 which are in planes normal to the axis of the cross pipe.

These nozzles are of such size, say about three-eighths of an inch in diameter, that they will not be subject to obstruction by 95 inequalities in the road dressing material.

Each nozzle is bored with a parallel portion where it connects to the duct 3 from the service pipe 2 and therefrom to the orifice is tapered with a curvature that will under the 100 pressure to be used project a practically cylindrical and compact jet.

The jets of road dressing material as they issue from these opposed converging nozzles form, on impact, a thin flat film 5, the 105 plane of which is substantially normal to the road surface and across its width.

These converging opposed nozzles constitute the essential feature of the invention, as the finely flattened film delivering directly 110

downward to the road surface and striking it with sufficient force to penetrate the interstices of the road metal and without sensible loss of heat, is the most effective means of applying a road dressing of oil or the like.

The spread of the film 5 being across the road only, the material is, with the movement of the vehicle applied to the road surface in a uniform sheet and therefore in a much more effective manner than it can be applied by means of a centrifugally divided spray, which, depositing in a circle, will with the movement of the vehicle apply a larger quantity in lines adjacent the middle of the transverse diameter than it will adjacent the ends of the same.

In applying these opposed nozzles to effect the spraying of a road surface, they are preferably arranged, as shown in Figs. 3 and 4, with three pairs of nozzles across the width of the road surface to be treated, the two outer ones delivering the film in the same plane and the middle one offset before or behind that plane, so that the extreme edges of the film from adjacent nozzles may overlap slightly to insure a uniform distribution over the road width without interfering.

We are aware that the principle of opposed converging jets is not broadly new, as it has been applied to obtain a finely divided spray of water or the like for moistening air, but believe that we have been the first to apply the principle of opposed jets to obtain a thin flat film of viscous material, such as road oil, by providing delivery nozzles which are designed to project an essentially compact jet, which on impact with its opposed jet flattens with it into a thin film and proceeds directly to the surface against which it is projected, instead of breaking up into a finely divided spray.

Having now particularly described our invention, we hereby declare that what we claim as new and desire to be protected in by Letters Patent, is:

1. A means for applying a thin flat film of a viscous material such as road oil, to a surface, said means comprising opposed nozzles having free discharge ends the axes of which nozzles angularly converge and

the bore of which is adapted to deliver a compact jet to the place of intersection, and means for delivering the material to both nozzles from a common source.

2. A means for applying a thin flat film of a viscous material such as road oil, to a surface, said means comprising nozzles having free discharge ends, the axes of which angularly converge in the same plane and the bore of which is adapted to deliver a compact substantially cylindrical jet to the place of intersection, and means for delivering the material to both nozzles from a common source.

3. A means for applying a thin flat film of a viscous material such as road oil, to a surface, said means comprising the combination with a pipe of ducts delivering from one side of the pipe to opposite sides, said ducts delivering into nozzles, the axes of which are in a plane normal to the axis of the pipe from which they are derived and converge to intersect below said pipe.

4. A means for applying a thin flat film of a viscous material such as road oil, to a surface, said means comprising the combination with a pipe of ducts delivering from one side of the pipe to opposite sides, said ducts delivering into nozzles, the axes of which are in a plane normal to the axis of the pipe from which they are derived and converge to intersect below said pipe, the bore of each nozzle being cylindrical for a short distance and thereafter contracted with a convex curvature to the outlet.

5. A means for applying a thin flat film of a viscous material such as road oil, to a surface, said means comprising the combination with a transverse pipe, of a series of opposed nozzles derived from such pipe, the axes of each pair of nozzles being in a plane normal to the axis of the transverse pipe and converging to intersect below it, the point of intersection of each alternate pair of nozzles being in the same plane, and those of the intervening nozzles being in a plane parallel thereto.

In testimony whereof we affix our signatures.

DAVID W. JOHNSTON.
